UNITED STATES PATENT OFFICE.

RICHARD A. SELWAY, OF CHICAGO, ILLINOIS.

FENCE-POST.

1,226,602.

Specification of Letters Patent. Patented May 15, 1917.

Application filed March 31, 1916. Serial No. 18,262.

To all whom it may concern:

Be it known that I, RICHARD A. SELWAY, a citizen of the United States, and a resident of the city of Chicago, county of Cook, and State of Illinois, have invented certain new and useful Improvements in Fence-Posts, of which the following is a specification.

My invention relates to fence posts and particularly to metal posts. More specifically my invention relates to fence posts constructed of sheet metal shaped to the desired form.

The primary object of my invention is to provide a metallic fence post of great strength and durability and of such construction that the strength is attained with the use of a minimum amount of material to the end that the cost of manufacture and transportation shall be reduced to a minimum. A further object of my invention is to provide a metallic fence post of the class under consideration which may be readily driven into the ground irrespective of the nature and condition of the soil and which, when driven, shall be self anchoring and which shall present a maximum amount of resistance to the ground to prevent lateral movement therein. A further object of my invention is to provide a fence post as mentioned equipped with means to facilitate attaching the fence fabric thereto and of such arrangement as to prevent chafing of the fabric. Other objects will appear herein-after.

With these objects in view my invention consists generally in a fence post formed of sheet metal, preferably sheet steel, tapered from end to end and substantially V-shaped in horizontal cross section with the edges bent back at an angle, preferably acute, to the sides of the V or body portion. My invention further consists in a fence post as stated in which the V or body portion merges into the lateral flanges by a rounded or curved portion against which the fence fabric is adapted to rest. My invention further consists in a fence post as mentioned further characterized by providing the lateral flanges with a series of apertures to receive the fabric securing means, said apertures being arranged beyond the curved or rounded portion above mentioned. My invention further consists in a sheet metal fence post having the horizontal cross section as above stated in which the sides of

the V are at an acute angle to each other, preferably about forty degrees and the lateral flanges at right angles or a little less to the sides of the V. My invention further consists in various details of construction and arrangement of parts all as will be fully described hereinafter and particularly pointed out in the claims.

My invention will be more readily understood by reference to the accompanying drawings forming a part of this specification and in which—

Figure 1 is a front elevation of a fence post embodying my invention, illustrating the same in position in the ground and the fence fabric attached thereto,

Fig. 2 is a side elevation of the same,

Fig. 3 is a horizontal section on the line 3—3 of Fig. 1, upon an enlarged scale, and

Fig. 4 is a section on the line 4—4 of Fig. 3.

Referring now to the drawings, 5 indicates the post which is formed of sheet metal; preferably steel, with the body portion V shaped in horizontal cross section and tapered from end to end, as shown. The lateral edges of the post are bent back forming flanges 6 which extend throughout the length of the post. The sides of the V shaped body are preferably at about forty degrees to each other and the flanges are arranged at eighty nine degrees or thereabout, to the adjacent sides of the body portion, these angles having been found, after a vast number of experiments to produce the greatest strength in the post in proportion to the weight of metal employed. While in practice I arrange the sides of the body portion at forty degrees to each other and the flanges at eighty nine degrees to the adjacent sides of the body, it is to be understood that these angles may be varied within reason without departing from the scope or spirit of my invention.

The flanges 6 are each provided with a plurality of pairs of apertures 7, staggered with relation to each other, as shown, and adapted to receive the wire fastenings 8 or other means employed for securing the fabric 9 of the fence to the post. The pairs of apertures 7 in the flanges 6 are staggered or off-set vertically with respect to the pairs of apertures in the other flange so as to facilitate securing the wires first to one flange 110 and then to the other, thereby preventing the twisting of the post in the ground.

It should be noted that the flanges 6 merge into the sides of the body portion by a well rounded portion 6', this construction being provided for two reasons; first 5 as it adds strength to the post and furthermore it forms a smooth bearing surface for the fence fabric to rest against so as to avoid chafing between the fabric and the post. It should also be noted that the apertures 7 are arranged in the flanges beyond the bearing points 6' so that any bur formed in making the apertures will not touch the fence fabric to chafe the same.

With a fence post of the construction described the maximum strength is obtained for the weight of material employed thereby producing a post of maximum efficiency and at a great saving in the amount of material. This is not only a saving in the cost 15 of manufacture and transportation but is also a great aid in handling and setting the posts. Also as the post increases in cross section as it approaches its lower end, it will be firmly anchored in the ground and 20 by reason of the angular positions of the sides of the body portion and the lateral flanges with relation to each other, the post presents the greatest resistance possible to lateral dislodgment in the ground.

30 Having described my invention what I claim as new and desire to secure by Letters Patent is:

1. A fence post formed of sheet metal tapered from end to end and V shaped in horizontal cross section, the lateral edges thereof being rebent to form flat flanges, the sides of the V shaped body portion being at an acute angle to each other and said lateral flanges being at an acute angle to the adjacent sides of the body, substantially as described.

2. A metallic fence post substantially V-shaped in cross section, the angle of the V being substantially forty degrees and having back-turned lips at its edges making an angle of substantially eighty-nine degrees with the legs of the V, substantially as described.

3. A fence post formed of sheet metal tapered from end to end and V shaped in horizontal cross section, the free edges of the sides of the V shaped body being rebent to form flanges at an acute angle to the adjacent sides of the body portion, there being

a well rounded portion connecting each 55 flange with its adjacent side and forming a seat for the fence fabric, substantially as described.

4. A fence post formed of sheet metal tapered from end to end and V shaped in horizontal cross section, the free edges of the sides of the V shaped body being rebent to form flanges at an acute angle to the adjacent sides of the body portion, there being a well rounded portion connecting each 60 flange with its adjacent side and forming a seat for the fence fabric, and said flanges being provided with perforations beyond the said rounded portions to receive fastening means for the fence fabric, substantially 65 as described.

5. A metallic fence post substantially V-shaped in cross section and having back-turned lips at its edges adapted to contact with the fence, there being fence securing 75 means located on said lips beyond the points of contact with said fence, substantially as described.

6. A metallic fence post substantially V-shaped in cross section and having rounded 80 back-turned lips at its edges adapted to contact with the fence, there being pairs of perforations located in said lips beyond the points of contact with said fence, substantially 85 as described.

7. A fence post formed of sheet metal tapered from end to end and blunt at each end and V-shaped in horizontal section, the angle of said V being substantially forty degrees, the free edges of the sides of the V-shaped body being rebent to form flanges at an angle of substantially eighty-nine degrees to the adjacent sides of the body portion, there being a well rounded portion 90 connecting each flange with its adjacent side 95 and forming a seat for the fence fabric, and said flanges being provided with pairs of perforations beyond the fence fabric seat, the perforations in said flanges being staggered with relation to each other, substantially 100 as described.

In testimony whereof I have signed my name to this specification in the presence of two subscribing witnesses.

RICHARD A. SELWAY.
